11 Claims. (Cl. 315—27)

This invention relates to time-base circuit arrangements for generating a saw-tooth deflection current in a deflection coil. More particularly, the invention relates to a deflection circuit comprising two switching elements of the semiconductor type, a source of supply voltage having two terminals, drive means for delivering signals to turn on and off at least one of said two switching elements, an overswing coil and a supply impedance. The first switching element is connected in series with an inductive load, formed by said deflection coil, across the two terminals of said supply source. The second switching element is connected in series with said overswing coil and said supply impedance across said two terminals of said source, but in such a manner that the free end of the series connection of the second switching element and overswing coil is connected to the other terminal of the supply source as the first switching element. An A.C. coupling is connected between the first switching element-to-inductive load junction and the supply impedance-to-overswing coil, second switching element junction.

Such a time-base circuit arrangement is already proposed in U.S. Patent No. 3,229,150.

In this proposed circuit arrangement, the first switching element is a diode which is turned on when the second switching element, a silicon controlled rectifier (SCR) is turned off automatically, and turned off when the second switching element is turned on by means of a drive signal. This on and off switching of the diode is accomplished by means of voltages developed in the time-base circuit arrangement itself. Especially at the instant the diode is turned off a large blocking voltage is developed across said diode (this blocking voltage jumps directly to said large value after the turn-off instant).

Due to the hole storage effect in the diode this blocking voltage causes an inverse current to flow, so that directly after the turning-off instant a large blocking voltage is developed across the diode and an inverse current is flowing so that the diode must be able to withstand a large dissipation.

In order to overcome said difficulty, the circuit arrangement in accordance with the present invention is characterized in that the first switching element is a transistor connected in its forward direction with respect to the polarity of the voltage delivered by the supply source, and the second switching element is a controlled rectifier connected in its backward direction with respect to the polarity of the voltage delivered by the supply source. The drive means deliver a first drive signal to turn off the transistor before the end of a scanning stroke and turn it on at the beginning of the scanning stroke and a second drive signal to turn on said controlled rectifier at the instant the transistor is turned off.

As will be seen, when comparing the drawings of the present application and that of U.S. Patent No. 3,229,150, the whole process is reversed. This means that the transistor-current is taken over by the SCR-current and that, after the transistor-current is reduced to zero, the voltage across it rises, but slowly, so that even when the transistor-current is not completely zero at the instant the voltage across it is rising, the transistor dissipation is still low.

In order that the invention may readily be carried into effect, an embodiment of a line time-base circuit arrangement with two controlled switching elements in accordance with the invention will now be described by way of example, with reference to the accompanying drawings, in which:

FIG. 1 shows an embodiment without an EHT transformer;

FIG. 2 shows curves of voltages and currents occurring in the embodiment of FIG. 1; and

FIG. 3 is an improved embodiment of the circuit arrangement of FIG. 1, which includes an EHT transformer and a core desaturation technique.

Referring now to FIG. 1, the arrangement described is suitable for use as a line time-base for a television receiver employing magnetic deflection. This circuit arrangement supplies a saw-tooth current waveform to an inductive load constituted by deflection coils L_y . The arrangement comprises, as the first switching element, a switching transistor T_1 having its emitter-collector path in series with said load L_y across a pair of D.C. supply rails, one grounded and one at a voltage $-V_{cc}$. A silicon controlled rectifier (SCR) D_1 , serving as the second switching element, is connected in series with an overswing coil L_2 and with an inductance L_1 , which serves as the supply impedance, across said rails with the inductance L_1 connected to the same rail as the transistor T_1 . An A.C. coupling C_1 is provided between the transistor-to-load junction and the inductance to overswing coil junction Q . It will be clear, however, that SCR D_1 and overswing coil L_2 can be interchanged, without changing the behaviour of the circuit arrangement.

The capacitance of capacitor C_1 constitutes, with the inductance of the load L_y and of the overswing coil L_2 , a tuned circuit having a period equal, or approximately equal, to four times the desired flyback period.

The controlled rectifier D_1 is a trigger device. The overswing coil L_2 is necessary in the circuit because it enables the transistor current to be taken over by the controlled rectifier current from the moment the transistor is turned off. In this example the arrangement includes, as will be seen, drive means consisting of a transformer comprising a primary winding P and two secondary windings S_1 and S_2 . The secondary winding S_1 is connected through an R.C.-network between the base and emitter electrodes of transistor T_1 . The secondary winding S_2 is connected between two points X and Y which, through a further R.C.-network, are coupled to the cathode and control electrodes of rectifier D_1 . To the primary winding P are applied impulses I . These impulses I induce in the secondary winding S_1 impulses which urge transistor T_1 to draw current from instant t_0 to instant t_2 (see also FIG. 2) and induce impulses in the secondary winding S_2 for turning the SCR on at the instant t_2 (FIG. 2) prior to the end of the scanning time (t_3) by a signal applied between its cathode and control or base electrode. It will be clear, however, that a transistor also could be used for the second switching element D_1 , but in that case the impulses at the secondary winding S_2 must also turn off this second transistor. Then difficulties occur due to the fact, as will be explained hereinafter, that the current through the second switching element must increase from the instant t_2 to the instant t_3 and thereafter decrease. This means that the impulses applied to the second switching element must be able to decrease the current through it from the instant t_3 . However, the impulses I applied to the primary winding must be of such a form that they, when induced in secondary winding S_1 , are able to begin with a turn-off of transistor T_1 at the instant t_2 , and to hold this transistor in a turned-off condition until the instant t_4 . This means the impulses I must have one polarity from in-

stant t_0 to t_2 and the other polarity from instant t_2 to t_4 as shown in FIG. 1, in which the broken line indicates ground potential.

When however, rectifier D_1 should be replaced by a transistor impulses I should have one polarity from instant t_2 to t_3 and of the other polarity from instant t_3 to the next instant t_2 . So special impulses would be needed for the second switching element. In the case where a SCR is used, it is only necessary to turn-on the SCR at the instant t_2 because its turn-off is accomplished automatically.

The operation of the circuit will now be explained with the aid of FIG. 2 in which FIG. 2(a) represents the collector current (I_c), FIG. 2(b) the emitter-collector voltage (V_e) of the transistor T_1 , FIG. 2(c) the voltage V_Q at the junction point Q and FIG. 2(d) the current i_{D1} through the rectifier D_1 .

At the start of the scanning period t_0 a negative going drive pulse is applied to the base of transistor T_1 with such amplitude as to cause the transistor T_1 to bottom so that a substantially linearly increasing current flows through T_1 (and L_y) throughout the major part t_0-t_2 of the stroke or scanning period.

Simultaneously with the circuit L_y-T_1 , a separate circuit is operated in the period t_0-t_2 , namely the circuit $T_1-C_1-L_1$. In this circuit C_1 and L_1 act as a tuned circuit having a very long period (long when compared with the period t_0-t_2) whose value is not at all critical. At the start of the scan, the capacitor C_1 will be assumed to be charged, the polarity being negative on the transistor side and positive on the other. During the stroke period this capacitor discharges resonantly through T_1 and the inductance L_1 and, when this discharge is completed at some instant between t_0 and t_1 , the voltage across C_1 (and L_1) will pass through zero and then change sign (see FIG. 2c instant t_2). At a later instant t_1 this voltage will have risen in resonant manner to a value equal to the supply voltage $-V_{cc}$. At this instant, the SCR (which has been in the off-state) has its reverse anode-cathode voltage reduced to zero. From t_1-t_2 the voltage across C_1 continues to rise and thus forward biases the SCR in anticipation of the trigger pulse to be obtained from winding S_2 . Since T_1 is bottomed by means of the pulses from winding S_1 , it acts virtually as a direct connection to ground. These latter changes can conveniently be followed as changes in the voltage at point Q as represented in FIG. 2(c) (the curvature of the sine-wave is only slightly visible, at instant t_0 , due to the very long period of L_1-C_1). The region in which this voltage exceeds V_{cc} (i.e. t_1-t_2) represents forward anode-cathode bias for the SCR.

The desired duration of the scanning stroke extends further than instant t_2 , namely up to instant t_3 . However, in order to anticipate the effect of hole storage in T_1 , and in accordance with the invention, transistor T_1 is turned off at an instant t_2 sufficiently early to allow the collector current and hole storage to have decayed to a negligible level at the instant t_3 . The SCR is triggered into conduction at the same instant t_2 by a signal derived from the drive waveform via connections X-Y. So another circuit path is opened, namely that through capacitor C_1 , load L_y , rectifier D_1 and completed through over swing coil L_2 .

This last circuit path is called the commutation circuit because the charge of capacitor C_1 is commutated into a discharge at the instant t_2 . The commutating current flowing through this commutation circuit enables the current in transistor T_1 to reduce to zero at the instant t_3 , because after the transistor current has been reduced to zero the discharge current can continue to flow through said commutation circuit. Thus the current through transistor T_1 is taken over in a so-called take-over period by the commutation circuit.

The decay of current in transistor T_1 during said take-over period (t_2-t_3) is shown in FIG. 2(a) to occur as a

half cycle of a sine-wave. This is due to resonance of L_2 and C_1 , L_2 having a small value chosen accordingly.

At some instant during the take-over period it is necessary to turn transistor T_1 off at its base, and to maintain this base turn-off voltage up to the end (t_4) of the flyback period. In this example the turn-off instant chosen, for convenience, is the instant t_2 since this allows the same drive waveform to be used to also turn on the SCR. The SCR D_1 is turned off automatically as will be explained more fully hereinafter.

Up to instant t_2 , the stroke current i_{Ly} has been rising substantially linearly. During t_2-t_3 the transistor T_1 remains conductive and therefore its collector electrode is substantially at ground potential. Thus the D.C. supply voltage V_{cc} is still applied across load L_y and the stroke current therein continues to rise up to instant t_3 as desired.

As mentioned above the initial discharge of capacitor C_1 is completed at the instant t_2 , when the voltage across this capacitor is zero. Thereafter capacitor C_1 will be charged such that its electrode connected to the junction point Q will become negative with respect to the electrode connected to the transistor T_1 . This charge will continue until the instant t_2 . Then transistor T_1 is turned off and SCR D_1 turned on. The turn-on of SCR D_1 means that the discharging of capacitor C_1 will be accelerated because inductance L_2 is now inserted. Thus a new L.C. circuit is formed by L_2 and C_1 . Therefore the voltage V_Q at the point Q will rise rapidly (see FIG. 2(c)) until the instant t_p at which instant the current through capacitor C_1 is zero. Thereafter the current through capacitor C_1 again changes direction. So the voltage V_Q starts to decrease and will be equal to $-V_{cc}$ at the instant t_3 . This is so because at the instant t_3 the current i_{D1} is maximum (see FIG. 2(d)) and because current i_c is zero (see FIG. 2(a)). The current through capacitor C_1 is practically equal to the current i_{D1} (neglecting the small current flowing through L_1 at this instant) and also equal to i_{Ly} so that in the resonant circuit, now formed by L_2 , C_1 and L_y , the current is maximum and thus the voltage across capacitor C_1 and the voltages across inductances L_y and L_2 will be zero. Therefore point Q gets the voltage $-V_{cc}$, assuming that the SCR has practically no impedance when turned on. After the instant t_3 , which is the start of the flyback period, the current will continue to flow through the resonant circuit L_2 , C_1 and L_y whereby the electromagnetic energy stored in inductance L_y during the period t_0-t_3 , will be transferred to electrostatic energy in the capacitor C_1 . Thus capacitor C_1 is once again charged resonantly by energy stored in L_y and, at an instant t'_4 (just prior to t_4) all this stored energy will have been transferred to capacitor C_1 (this is the charged state postulated initially). This resonant charging of C_1 occurs during a time period equal to one quarter of the time period of the resonant circuit formed by L_y , L_2 and C_1 . The accompanying current flow through the loop circuit L_y , C_1 , L_2 and SCR changes sign when C_1 is fully charged. Since the SCR cannot conduct in its reverse direction the said current flow would cease at this instant t'_4 . Thus there is a short initial delay t'_4-t_4 due to the hole storage effect in the SCR because all the holes are not removed until the time t_4 . Therefore the instant $t_4=t_0$ is the effective end of flyback and the start of the next stroke, and T_1 is arranged to be then turned on (at its base) by the drive waveform.

With regard to the choice of the value of C_1 and L_2 , the period of the tuned circuit L_y , L_2 , C_1 was given generally as four, or approximately four, times the desired flyback period. This is of special importance as will be seen from FIG. 2(b), because with this choice of the tuned circuit L_y , L_2 , C_1 , the rise of the collector voltage V_c , starting at the instant t_3 was not very steep, and this rise would be much steeper if the period of the tuned circuit L_y , L_2 , C_1 was chosen to be two times the desired flyback period.

In the present specific example, the period chosen for the tuned circuit L_y , L_2 , C_1 (which is equal to four times the period t_3-t_4) is less than four times t_3-t_4 in order to accommodate the turn-off delay of the SCR due to hole storage.

The said delay in the SCR turn-off has an effect in that C_1 discharges back into L_y between instants t_4 and t_4 thus causing a small current in L_y in a direction opposite to that which would be produced by a supply-voltage V_{cc} through T_1 . The new current stroke starts from this level of inverse current which flows through transistor T_1 (see FIG. 2(a)) by virtue of the transistor being capable of conducting in its reverse direction with its emitter-collector section operating as a forwardly conducting diode while the inverse current lasts.

It may be added that throughout the scanning period the circuit T_1 , C_1 , L_1 will carry a current (which to a first approximation may be regarded as constant) which will be in the forward direction of current flow through the transistor. This current will back off the said initial inverse current but it is found in practice that there remains a residual inverse current flow through the transistor.

In conclusion, it will be seen from FIGS. 2(a) and 2(b) that, although voltage is present across the transistor in the flyback period t_3-t_4 , there is no current flow so that there is substantially no power dissipation in the transistor during flyback time.

Even if the transistor current was not exactly zero at the instant t_3 , the transistor dissipation will be low because the collector voltage V_c is only rising slowly from the instant t_3 (see FIG. 2(b)).

This is due to the fact that the take-over period t_2-t_3 is chosen before the flyback period t_3-t_4 . This is possible because two switching elements are used which can be switched by means of the same impulses I which are applied to the drive means (transformer with windings P , S_1 and S_2) with such polarities to both switching elements that the transistor T_1 is turned off at the instant the SCR D_1 is turned on. So not only the hole storage effect of transistor T_1 is eliminated but also its total dissipation is reduced.

The A.C. voltage for the display tube E.H.T. can readily be obtained in a conventional manner by connecting a step-up transformer in parallel with the scanning inductance L_y . However, the circuit arrangement of FIG. 1 can be slightly modified to desaturate the core of the EHT transformer and thereby provides a substantial economy in the core volume.

In FIG. 3 the primary L_p of the EHT transformer having n.p. turns is connected in parallel with the series connection of scanning inductance L_y and capacitor C_s . An object of the capacitor C_s is to introduce a small S-shaped wave correction on the linear saw-toothed scanning wave to correct the scanning non-linearity caused by a substantially flat-faced display tube.

It also obviates picture shift by removing the D.C. component from the coils L_y .

The inductance L_1 of FIG. 1 includes the series combination of a further inductance L_s having n.s. turns.

As a result, all the D.C. current flows through the EHT primary L_p and tends to saturate its core. This is prevented by the inclusion of the additional winding L_s in which the number of turns thereof is chosen so that $n.s. \times I_D$ equals $n.p. \times I_p$. The winding L_H constitutes the secondary of the EHT transformer which, after conventional rectification and smoothing, supplies the EHT voltage to the final accelerating electrode of the display tube.

Because of the voltage developed across L_s during the scanning period, the inductance value of L_1 will have to be slightly changed in order to achieve the same circuit function.

The arrangement of FIG. 1 may, for example, employ the following set of components and values suitable for a 625-line system having a total line cycle time of 64 μ s.: 75

6
Table

Supply V_{cc}	volts	12
Period t_2-t_3	μ s	4
Period t_3-t_4	μ s	14.5
5 Transistor T_1	Mullard type AU 101

What is claimed is:

1. A circuit for generating a saw-tooth deflection current having a given flyback period in a deflection coil, comprising first and second switching elements of the semiconductor type, a source of supply voltage having two terminals, drive means for delivering signals to turn on and off at least one of said switching elements, an overswing coil and a supply impedance, first means connecting said first switching element in series with said deflection coil across said two terminals of said supply source, second means connecting said second switching element in series circuit with said overswing coil, third means connecting said series circuit in series with said supply impedance across said two terminals of said source so that the free end of the series circuit comprising said second switching element and overswing coil is connected to the other terminal of the supply source than that to which the first switching element is connected, said first connecting means being arranged to form a first junction between the first switching element and deflection coil, said third connecting means being arranged to form a second junction between said supply impedance and said series circuit, A.C. coupling means interconnecting said first and second junctions, characterized in that the first switching element is a transistor, poled in the forward direction with respect to the polarity of the voltage delivered by the supply source, and the second switching element is a controlled rectifier poled in the reverse direction with respect to the polarity of the voltage delivered by the supply source, said drive means being arranged to deliver a first drive signal to turn off the transistor before the end of a scanning stroke and turn it on at the beginning of the scanning stroke and a second drive signal to turn on said controlled rectifier at the instant the transistor is turned off.
2. A circuit arrangement as claimed in claim 1, wherein in said A.C. coupling means is a capacitor, characterized in that said capacitor in conjunction with the deflection coil and the overswing coil form a flyback circuit having a period approximately equal to four times said flyback period.
3. A circuit arrangement as claimed in claim 2, wherein in the time period between the turn-off of the transistor and the beginning of the flyback period is equal to one-half of the period of the resonant circuit formed by said coupling capacitor and said overswing coil, said time period being substantially equal to the time necessary to drive the holes out of the base region of transistor by means of said first drive signal when turning off said transistor.
4. A circuit arrangement as claimed in claim 1, wherein in said drive means comprise a transformer having one primary and two secondary windings, means for supplying to said primary winding a drive signal, means connecting the first secondary winding to the control electrode of the transistor for delivering thereto said first drive signal, and means connecting the second secondary winding to the control electrode of the controlled rectifier for delivering thereto said second drive signal.
5. A circuit arrangement as claimed in claim 1, further comprising means for generating an A.C. voltage for the EHT supply to the display tube, said voltage generating means comprising a capacitor effectively connected in series with the deflection coil, means connecting the

primary winding of an EHT step-up transformer across said series combination, means connecting a further inductance in series with the supply impedance which is connected in series with the controlled rectifier, wherein said further inductance is magnetically coupled to said EHT primary winding, the turns ratio of the EHT primary winding and the further inductance being chosen so as to substantially desaturate the core of said EHT transformer.

6. A circuit for generating an alternating current of sawtooth waveform in an inductive load comprising, a source of direct voltage, a first series circuit connected across said voltage source comprising said inductive load and semiconductor amplifier means having a control electrode for controlling the current flow therein, a second series circuit connected across said voltage source comprising a controlled rectifier having a gate electrode and connected in series with an inductance and impedance means, said semiconductor amplifier means being poled in the forward direction with respect to said voltage source and said controlled rectifier being poled in the reverse direction with respect to said voltage source, a capacitor interconnecting said first and second series circuits to form first and second closed loop circuits, said first closed loop circuit comprising, in series, said inductive load, said controlled rectifier, said inductance and said capacitor, said second loop comprising, in series, said impedance means, said semiconductor amplifier and said capacitor, and drive means coupled to said control and gate electrodes for simultaneously applying thereto drive signals of a polarity tending to turn off current flow in said semiconductor amplifier and to turn on current flow in said controlled rectifier, respectively.

7. A circuit as described in claim 6, wherein said first closed loop circuit forms a tuned circuit having a period approximately equal to four times the flyback period of said sawtooth alternating current.

8. A circuit as described in claim 6, wherein said drive means is arranged to apply to said control electrode a drive signal tending to turn on current flow in said semiconductor amplifier at the beginning of the stroke period of said sawtooth alternating current, and wherein said second closed loop circuit is arranged to form a tuned circuit having a very long period relative to said stroke period.

9. A circuit as described in claim 6, wherein said drive means is arranged to turn said semiconductor amplifier on and off at least once during each cycle of said sawtooth alternating current, whereby said second closed loop circuit is closed via said semiconductor amplifier during the stroke period thereby to resonantly discharge said capacitor and said first closed loop circuit is closed via said controlled rectifier during the flyback period thereby to resonantly charge said capacitor.

10. A circuit for generating an alternating current of sawtooth waveform in an inductive load comprising, a source of direct voltage, a bridge circuit comprising first and second branches connected across said voltage source, said first branch comprising first and second series-connected arms comprising a transistor poled in the forward direction relative to said voltage source and said inductive load, respectively, said second branch comprising third and fourth series-connected arms, said third arm comprising a supply impedance and said fourth arm comprising, in series, an overswing coil and a controlled rectifier poled in the reverse direction relative to said voltage source, A.C. coupling means connected between the junction of said first and second arms and the junction of said third and fourth arms, signal drive means coupled to the control electrode of said transistor and to the gate electrode of said controlled rectifier, said drive means being arranged to supply a first drive signal to said control electrode to turn said transistor on and off at least once during each cycle of said sawtooth alternating current and to supply a second drive signal to said gate electrode so as to turn on said controlled rectifier at the same time in each cycle that said first drive signal turns off said transistor.

11. A circuit as described in claim 10, wherein said transistor and said controlled rectifier are arranged in opposed arms of said bridge circuit.
